United States Patent Office

Des. 229,738

Patented Jan. 1, 1974

229,738

SPOON

Donald Wallace, Croton-on-Hudson, N.Y., assignor to
H. E. Lauffer Co., Inc., Somerset, N.J.

Filed July 25, 1972, Ser. No. 274,919

Term of patent 14 years

The portion of the term of the patent subsequent to
Jan. 1, 1988, has been disclaimed

Int. Cl. D7—03
U.S. Cl. D7—137

FIG. 1 is a top view of a spoon showing my new design;

FIG. 2 shows a side view thereof;

FIG. 3 shows a bottom view thereof;

FIG. 4 shows a lengthwise sectional view thereof;

FIG. 5 shows a front end view looking in the direction of the bowl portion rearwardly toward the handle portion;

FIG. 6 is a rear end view thereof looking in the direction from the handle toward the bowl portion;

FIG. 7 is a sectional view thereof looking in the direction of arrows 7-7 of FIG. 1;

FIG. 8 is a sectional view thereof looking in the direction of arrows 8-8 of FIG. 1; and

FIG. 9 is a sectional view thereof looking in the direction of arrows 9-9 of FIG. 1.

I claim:

The ornamental design for a spoon, as shown.
